ADJUSTABLE SASH-LOCK.

1,072,100.

Specification of Letters Patent.

Patented Sept. 2, 1913.

Application filed July 19, 1912. Serial No. 710,443.

To all whom it may concern:

Be it known that I, LEWIS ELMER DE NEERGAARD, a citizen of the United States, residing in the city of Port Chester, county 5 of Westchester, and State of New York, have invented certain new and useful Improvements in Adjustable Sash-Locks, of which the following is a full, clear, and exact description, reference being had to the 10 accompanying drawings, forming part of this specification.

This invention relates to improvements in sash locks and particularly to that class of sash locks comprising two members slidably 15 connected to each other adapted to clamp the device between the outer sash and the frame molding of a window so as to secure the sashes in position, and its main object is to provide a sash lock of a simple and inexpensive construction, adapted to be used in connection with usual sizes of windows.

A further object of this invention is to provide in a sash lock of the kind described comprising two members each having a serrated flange, means for automatically moving one of the flanges out of engagement from its respective clamped surface, to insure the free up and down motion of the 20 window sashes.

30 A still further object is to provide in a sash lock comprising two clamping members slidably connected to each other, improved means for adjusting the range of the device independently of the operating means.

35 With these and other objects in view as will more fully appear as the description proceeds, this invention consists in certain constructions and arrangements of parts such as will be hereinafter fully described 40 and claimed in the appended claims.

The main object of a device of the character of the one to which this invention refers is to fasten the sash in any position and to prevent the same from being opened from 45 the outside. Several devices having means for clamping the outer sash of a window against the frame molding have been heretofore made, and among others I may cite a sash lock forming the object of an application for a patent previously filed by me having for title "Sash lock," Serial No. 676,916, filed Feb. 10, 1912, of which the present device represents an improvement. In the drawings pertaining to said application, I show an extension adjustment for

rendering the device adaptable to any size of window, said adjustment being obtained by fixing the pivot of the cam-acting member at different places on the bearing plate; the relation between said cam-acting member and the adjustable plate remaining always the same. I have found however the construction and operation of said extension adjustment to be rather complicated and not readily understood by everybody; furthermore, 60 I found that by adopting the construction forming the object of the present invention, the cost of manufacturing the device could be reduced and at the same time its construction simplified. In putting into practical use the sash lock forming the object of the said previous application, I also found that the operation of the same was not entirely satisfactory inasmuch as when retracting the bearing plate by means of the 65 cam-acting member, the bearing plate had to be pushed by hand away from its clamping position in order to entirely free the lower sash and avoid the scraping of said adjusting plate against the inner molding 70 when moving said sash up or down; this evidently constitutes quite an inconvenience because said shifting by hand is liable to be forgotten quite often and the inner molding 75 of a window frame scratched on account 80 of it. In designing my improved device, I have sought to avoid these imperfections and I have otherwise improved the construction of my lock as will be apparent from the 85 forthcoming description.

90 Referring to the drawings, Figure 1 is a front view in elevation of my device as applied to a window sash in its clamping position; Fig. 2 is a front view in elevation of the same showing the cam-acting member turned around on the device ready to be adjusted for extension; Fig. 3 is a front view in elevation of the bearing member showing a spring which may be used for shifting the same when the device is released from its 95 clamping position, Fig. 4 is a side sectional view in elevation of the same; Figs. 5 and 6 are respectively a side view in elevation, and a plan view from the top of the same; Fig. 7 is a front view in elevation of the adjustable member; Fig. 8 is a cross sectional plan view of the same; Fig. 9 is a plan view of the dog used in connection with the adjustable member; Fig. 10 is a side sectional view of the same; Fig. 11 is a detail front 100 105 110

view in elevation showing different means for shifting the bearing plate away from its clamping position when the clamping action of the device is released; and Fig. 5 12 is a detail plan view from the top of the same.

My device is essentially composed of a bearing member 20, to which is slidably connected an adjustable member 21, controlled 10 by an operating member 22 mounted on said bearing member 20; part 21 may be slidably connected to part 20 in any convenient manner, and the drawings show a preferred form of construction in which part 21 is retained by part 20 by means of an upper flange 23 and lower flanges 24, 25, bent over the same. Bearing member 20 is provided with a flange 26 adapted to rest against the frame molding and adjustable member 21 is provided with an inner flange 27 adapted 20 to rest against the outer sash. Said flanges are provided with serrations 28, 29 directed outwardly and preferably both upwardly and downwardly, and adapted therefore to lock the device against the upward and 25 downward motion. One of the said slidable members and preferably the inner member of bearing member 20, is provided with a right angle lug or projection 30, having longitudinal elongated slots 31, 32; said slots are used for the passage of screws 33 retaining the device attached to the inner sash of a window.

The drawings show lug or projection 30 35 at the lower part of the device, the same being intended for the usual style of window in which the inner sash normally occupies the lower section of the same; by means of lug or projection 30, this device can therefore be attached to the top rail of said inner sash, as illustrated in Fig. 1.

The openings for the passage of the screws are preferably made elongated as shown, to allow the device to be slightly moved when 40 released from its clamping position, so as to detach both flanges from the respective surfaces formerly clamped, and to permit the free motion of the window sashes. To this object I provide means exerting a pressure 45 against the inner molding and therefore pushing the device away from the same when the cam-acting member is operated, so as to release its clamping action. This object may be attained in any suitable manner, but I prefer to use, as shown in the 50 drawings, a spring 34 attached to flange 36, and projecting through opening 35, provided in the same, said spring exerting a pressure against the inner molding of the 55 window frame; I have found said spring to be both inexpensive and efficient for the 60 purposes specified.

To effect the locking of the device, I provide a cam-slotted member 22 having a slot 65 36 and pivoted at 37 to bearing member 20.

The same can be pivotally mounted in any suitable manner, but I prefer to mount the same in the way shown in the drawings, Fig. 4, where it is seen that the pivot is formed by forcing out metal from part 20, 70 so as to form a circular projection, and then after having inserted part 22 over the same by bending the sides of said projection over said part 22 forming retaining flange 38. These operations can be entirely performed 75 by dies, the result being a very strong construction at an exceedingly low cost.

It is obvious that in a device of moderate size in which the motion of the adjustable member is obtained by means of a cam of the shape shown in the figures, the range of said motion is necessarily limited if the lock is expected to exert a strong clamping action; and therefore if the device is to be adapted for every size window it will be necessary to provide an extension adjustment for the same. I have devised a very simple and inexpensive way of effecting this adjustment, which is shown in the drawings and which I will now describe.

Part 21 is provided with a series of openings 39, equally distanced, and part 20 is provided with a notch 40 providing a clear space adapted to receive an element 41, which can be loosely mounted on said part 21. Said element is provided with depending lugs 42, 43, adapted to be inserted through any two openings 39; said element can therefore be inserted through part 21 at different points according to the number of openings 39 provided. Furthermore, said element is provided with an upwardly projecting lug 44 adapted to enter through slot 36 in member 22, and preferably bent at 45 over the peripheral portion 46 of said 95 part 22.

From the drawings it is seen that when said element 41 is in one of its operative positions, the same is retained between adjustable member 21 and cam-acting member 22, it being impossible for the same to come away. In order to adjust the device to different sizes of windows, at the end of slot 36 in cam-acting member 22, I provide an opening 47 large enough to clear element 41. If said cam-acting member 22 is rotated far enough in the releasing direction, said opening 47 will uncover element 41, as shown in Fig. 2, and said element can then be removed by hand; parts 20 and 21 can 110 then be adjusted by hand to the desired width, element 41 reinserted through the openings 39, which are uncovered by opening 47, and member 22 rotated in the reverse direction causing slot 36 to reengage 115 lug 44 of element 41.

When the device has been attached to a window after having been adjusted to the proper size, it is impossible for element 41 120 to come away inasmuch as handle 48 of 125

member 22 striking against the outer window sash will prevent the rotation of part 22 at a point far enough to uncover element 41; permanency in the operation of the device is therefore assured.

As hereinbefore explained, when cam-acting member 22 is rotated toward the left so as to release part 21, spring 34 pressing against the inner molding will force flange 26 away from the same; therefore the device will automatically clear both the surfaces which were formerly clamped by the same. The shifting of part 20 away from the inner molding can be effected in many different ways; for instance, in Figs. 11 and 12, I show one of the ways which may be adopted in place of spring 34. In said figures 49 is an element pivotally mounted at 50 to lug 30; said element has an arm 51 resting against the inner molding of the window to which the device is applied, and a lug 52 upwardly projecting in the same plane with cam-acting member 22. When said cam-acting member 22 is rotated far enough toward the left so as to release the adjustable member, nose of the same will exert a pressure against lug 52 and therefore by action through arm 51 against the molding, will cause both 51 and lug 30 to move away from said molding, thus causing the flange of the bearing member to clear the same.

In designing my device, I have carefully avoided the use of threaded parts which are usually more costly to manufacture than die produced sheet metal parts, and I also have avoided as much as possible the use of parts projecting from the surface of the device, which would render the same less attractive in design and appearance.

The slotted member controlling the sliding relative motion of the two clamping members of which my device is composed, can be made with a detached handle or with a handle integral therewith, as desired; and the slot provided in the same may be caused to follow any suitable curve which will fulfil the requirements of the device.

It is to be understood that my device can be modified in its various details without substantially departing from the spirit of my invention, and I reserve myself the right of bringing to the same all those changes and modifications which may be rendered necessary or useful to meet special requirements of individual cases, and which fairly enter into the scope of the appended claims.

I claim:

1. In a sash lock, the combination of a bearing plate, an adjustable plate slidably connected thereto, a cam-acting member pivotally mounted on said bearing plate, and a member actuated thereby adapted to be fixed on said adjustable plate at different points; for the purposes as set forth.

2. In a sash lock, the combination of a

bearing plate, an adjustable plate slidably connected thereto provided with a series of slots, a slotted cam-acting member pivotally mounted on said bearing plate, and an element having prongs adapted to be inserted through said slots, said element being retained between said adjustable plate and said cam-acting member, and having a part projecting through the slot of said cam-acting member; substantially as set forth. 70

3. In a sash lock, the combination of a bearing plate, an adjustable plate slidably connected thereto provided with a series of slots, a cam-acting member pivotally mounted on said bearing plate provided with a slot and with an enlarged opening at the end of said slot, and an element adapted to be inserted through said opening, said element having prongs entering said slots and a part projecting through the slot of said cam-acting member, and being retained between said adjustable plate and said cam-acting member; substantially as described, and for the purposes as set forth. 75

4. In a sash lock and in combination with a bearing member adapted to be movably attached to the lower sash of a window, an adjustable member slidably connected thereto, and means for operating the same, means for automatically moving said bearing member away from its clamping position when the clamping action of said adjustable member is released by said operating means; for the purposes as set forth. 90

5. In a sash lock the combination of a bearing plate and an adjustable plate slidably connected to each other having serrated flanges, means for operating the same, a lug projecting from one of the said plates for movably attaching the device to the inner sash of a window and a spring attached to the said plate tending to move the same out of clamping position; substantially as set forth. 100

6. In a sash lock the combination of a bearing plate, provided with a lug adapted to movably attach the same to the inner sash of a window, an adjustable plate slidably connected to said bearing plate, a cam-acting member pivotally mounted on said bearing plate controlling the motion of said bearing plate, and means for automatically pushing said bearing plate out of clamping position when said adjustable member is retracted by said cam-acting member; substantially as set forth. 105

7. In a sash lock the combination of a bearing plate, provided with a lug adapted to movably attach the same to the inner sash of a window, an adjustable plate slidably connected thereto, provided with a series of slots, serrated flanges integral with said plates, a slotted cam-acting member pivotally mounted on said bearing plate, an element having prongs adapted to be inserted 115

through said slots, said element being retained between said adjustable plate and said cam-acting member, and having a part projecting through the slot of said cam-acting member, and a spring projecting through the flange of said bearing member tending to push the same away from its clamping position; substantially as set forth.

8. In a sash lock the combination of a bearing plate provided with a lug adapted to movably attach the device to the inner sash of a window, an adjustable plate slidably connected thereto provided with a series of slots, serrated flanges integral with said plates, a cam-acting member pivotally mounted on said bearing plate provided with a slot and with an enlarged opening

at the end of said slot, an element adapted to be inserted through said opening, said element having prongs entering said slots, 20 and a part projecting through the slot of said cam-acting member and being retained between said adjustable plate and said cam-acting member, and a spring projecting through the flange of said bearing plate 25 tending to push the same away from its clamping position.

In testimony whereof I affix my signature in presence of two witnesses.

LEWIS ELMER DE NEERGAARD.
